ROLLER FOR SEED BEDS

Jerry A. Taylor, P.O. Box 669, Dixon, Calif. 95620

Filed June 5, 1967, Ser. No. 7,359

Term of patent 14 years

(Cl. D39—1)

FIGURE 1 is a side elevational view of a roller for seed beds showing my new design;

FIGURE 2 is a front elevational view;

FIGURE 3 is a top plan view;

FIGURE 4 is a fragmentary view to an enlarged scale of the roller mesh; and,

FIGURE 5 is a fragmentary sectional view to an enlarged scale, the plane of the section being indicated by the line 5—5 in FIGURE 4.

I claim:

The ornamental design for a roller for seed beds, as shown.
